Primary Examiner — Karen E Eldridge Powers

(57) **CLAIM**

The ornamental design for a dental floss brush, as shown and described.

DESCRIPTION

FIG. 1 is a front elevational view of a dental floss brush showing my new design;

FIG. 2 is a rear elevational view thereof;

FIG. 3 is a left side elevation view thereof;

FIG. 4 is a right side elevation view thereof;

FIG. 5 is a top plan view thereof;

FIG. 6 is a bottom plan view thereof; and,

FIG. 7 is a perspective view thereof.

The broken lines shown in dental floss brush form no part of the claimed design.
